UNITED STATES PATENT OFFICE.

GEORGE W. WATSON, OF BOSTON, MASSACHUSETTS, ASSIGNOR OF ONE-FOURTH TO
ALLEN & DAGGETT, INC., OF NORWICH, CONNECTICUT, A CORPORATION OF CON-
NECTICUT.

CHILD'S VEHICLE.

1,317,407.

Specification of Letters Patent. Patented Sept. 30, 1919.

Application filed September 21, 1917. Serial No. 192,601.

To all whom it may concern:

Be it known that I, GEORGE W. WATSON, a citizen of the United States, residing at Boston, in the county of Suffolk and State 5 of Massachusetts, have invented new and useful Improvements in Children's Vehicles, of which the following is a specification.

This invention relates to a child's vehicle, the object of the invention being to provide 10 a toy for children which can be propelled by the feet of the person using the same while seated thereon, by pushing with the feet upon the floor or ground upon which the vehicle rests at the time it is being used.

15 The principal object of the invention is to provide a vehicle of the character set forth which is adaptable for children of different sizes and ages and this is accomplished by providing a seat which is adjustable toward 20 and away from the body portion of the vehicle.

Another object of the invention is to provide a seat which can be rotated upon the body portion of the vehicle so as to readily 25 and easily accommodate itself to different positions assumed by the body of the user.

The invention consists in the combination and arrangement of parts set forth in the following specification and particularly 30 pointed out in the claims.

Referring to the drawings:

Figure 1 is a side elevation of my improved child's vehicle.

Fig. 2 is a plan view of the same.

35 Like numerals refer to like parts throughout the views of the drawings.

In the drawings, 5 is the body portion of the vehicle consisting of a flat board having straight sides 6. 7 is a bolster attached to 40 the rear end of the body portion 5 and having wheels 8 rotatably mounted thereon. Said bolster is provided with a brace 9 extending therefrom to the under side of the body portion 5 to which it is fastened.

45 A steering member 10 is rotatably mounted at 11 in the body portion 5 adjacent to the front end thereof. Said steering member is provided with a handle 12 and has a wheel 13 rotatably mounted at 14 upon the 50 lower end thereof.

55 Abutment blocks 15 are fastened to the top of the body portion 5 against which the child may place his feet. A nut 16 is fastened to the under side of the body portion 5 and forms in effect a portion thereof and

said nut is engaged by a screw 17 which has a flange 18 at its upper end and is fastened to a circular seat 19, whereby said seat is caused to have screw-threaded connection with said body portion. 60

The general operation of the toy hereinbefore described is as follows: The child sits upon the seat 19 and straddles the body portion 5; placing his feet upon the ground he propels the vehicle, at the same time 65 steering it by means of the handle 12, steering member 10 and wheel 13. When the vehicle is moving on a down grade or when it has received momentum enough from the pushing of the same, as hereinbefore described, the child lifts his feet and places them against the abutment blocks 15. 70

It is evident that the seat 19 may be raised and lowered to accommodate children of different sizes and ages and that as the 75 child propels the vehicle any slight change in the position of the body is accommodated by the rotation of the seat 19.

By providing the abutment blocks 15 on either side of the steering post 10 the control 80 and the steering of the device are greatly facilitated and the comfort of the user is enhanced by doing away with the necessity of bending one's body forward in order to gain control of the steering member, and at 85 the same time allowing of a backward inclination of the body of the user with his feet on the abutment blocks and without disturbing the balance of the device by being either forced to bend the body forward for 90 steering purposes or by the child's tendency of pushing himself on the flat body of the vehicle too far in the backward direction. An additional safeguard against the over-balancing thereby incurred is afforded by 95 the provision of the rotatable and adjustable seat which is preferably arranged somewhat in front of the center of the rear wheels and which counteracts the tendency of the child to slide too far to the rear along the 100 car body in his effort to gain a comfortable balancing position, and the proper balancing position is always insured thereby while at the same time affording an opportunity to the user of swinging his body around and inclining the same in all directions without his 105 losing his hold on the car body and on the abutment blocks which latter with this end in view are preferably downwardly and backwardly inclined so that their faces are 110

to the rear of the steering post, and in order to further assist the user in assuming the inclined position the seat is preferably concentric to its rotating center 17, and is marginally unobstructed, having neither back nor arm supports to interfere with the swinging movement of the body.

Having thus described my invention, what I claim and desire by Letters Patent to secure is:

In a child's vehicle adapted to be propelled by the action of the user's feet upon the traveling surface, in combination an elongated vehicle body, front end supporting means and rear end supporting means respectively mounted near the respective ends of said body, a marginally unobstructed substantially circular seat rotatably mounted

on said body in advance of said rear supporting means, a steering post at the front end of said body and operatively connected to said front supporting means, downwardly and rearwardly inclined abutting means adapted for contact with the feet of the user upon the upper surface of the elongated body, and substantially confined between the steering post and the sides of the elongated body.

In testimony whereof I have hereunto set my hand in presence of two subscribing witnesses.

GEORGE W. WATSON.

Witnesses:

CHARLES S. GOODING,
SYDNEY E. TAFT.
